UNITED STATES PATENT OFFICE.

ROBERT E. SMITH, OF MEXICO, MISSOURI.

RAILWAY-BED CONSTRUCTION.

SPECIFICATION forming part of Letters Patent No. 762,208, dated June 7, 1904.

Application filed February 23, 1904. Serial No. 194,954. (No model.)

To all whom it may concern:

Be it known that I, ROBERT E. SMITH, a citizen of the United States, residing at Mexico, Audrain county, State of Missouri, have invented certain new and useful Improvements in Railway-Bed Construction, of which the following is a specification containing a full, clear, and exact description, reference being had to the accompanying drawings, forming

10 a part hereof.

My invention relates to railway-beds, my object being to reduce the amount of work required for ties in railway-bed construction, to give the bed increased strength and durability, and to provide for adjustment when the bed sinks or otherwise changes its position.

My improved railway-bed construction comprises the combination, with a suitable grade, 20 of two parallel rows of ties laid end to end and overlapping, pins inserted vertically through the overlapping ends of the ties, anchors embedded in the grade below and between the rails, tie-rods connecting the rails, 25 elastic anchor-rods connecting the ends of the tie-rods inside of the rails to the anchors, there being turnbuckles incorporated into said anchor-rods for adjusting the lengths of the anchor-rods, anchor-plates embedded in 30 the grade outside of the rails, turnbuckles connecting said anchor-plates to the ties, and rows of cement embedded in the grade between the earth and the ties.

In the drawings, Figure 1 is a cross-section 35 of a railway-bed construction embodying the principles of my invention. Fig. 2 is a top plan, parts being shown in dotted lines and parts being broken away. Fig. 3 is a perspective of one of the tie-rods. Fig. 4 is a perspective showing a connection between two ties.

Referring to the drawings in detail, the wooden ties 5 are half-lapped at their meeting ends and connected together by pins 6, inserted vertically. The rails 7 are laid longitudinally of the ties, said rails being connected by the tie-rods 8. The ties are laid upon rows of cement 9, said rows of cement being embedded into the earthen grade 10. The 45 anchors 11 are embedded into the blocks of

cement 12, said blocks of cement being cast into position in the grade below and between the rails. The anchor-rods 13 extend upwardly and outwardly from the anchors 11, the central portions 14 of said anchor-rods 55 being coiled or crimped to render said anchor-rods elastic under an endwise strain. The nipples 15 are forged integrally with the tie-rods 8, and turnbuckles 16 connect the nipples 15 to the upper ends of the anchor-rods 60 13, so that when the grade settles or the ties shift upon the grade the tension upon the anchor-rods may be adjusted by the turnbuckles or compensated by the elastic portions 14. Blocks 17, of cement, are cast integral with the 65 rows 9, said blocks being outside of the ties, and the anchor-plates 18 are embedded in said blocks 17. The anchor-fastenings 19 are bolted to the ties, and turnbuckles 20 connect these fastenings to the anchor-plates 18, thus 70 forming an adjustable connection between each block 17 and the corresponding tie.

My railway-bed construction will effectually prevent the ties and rails from moving laterally upon the grade and will effect a great 75 saving in ties.

I claim—

1. A railway-bed construction comprising the combination with a suitable grade of two parallel rows of ties half-lapped at their meeting ends, pins inserted vertically through the half-lapped ends, anchors embedded in the grade below and between the rails, tie-rods connecting the rails, elastic anchor-rods connecting the ends of the tie-rods to the anchors, and anchor-plates embedded in the grade and connected to the ties outside of the rails. 80

2. A railway-bed construction comprising the combination with a suitable grade, of two parallel rows of cement embedded in the grade, 85 ties laid end to end upon the rows of cement, anchors embedded in the grade below and between the rails, and elastic anchor-rods connecting the anchors to the rails. 90

3. A railway-bed construction comprising 95 the combination with a suitable grade, ties upon the grade, anchors embedded in the grade below and between the ties, rails upon the ties, anchor-rods extending upwardly from the anchors, tie-rods connecting the rails and turn- 100

buckles connecting the anchor-rods to the tie-rods.

4. In a railway-bed construction, a suitable grade, ties laid end to end upon the grade and half-lapped, rails mounted upon the ties, anchors embedded in the grade between the rails, anchors embedded in the grade outside of the rails and turnbuckles adjustably connecting said anchors to the rails.

10. 5. In a railway-bed construction, the combination with a suitable grade, of two rows of cement embedded in the grade, two rows of ties laid end to end upon the rows of cement and half-lapped, pins inserted vertically in the half-lapped ends of the ties, anchors embedded in the grade below and between the rails, tie-rods connecting the rails, elastic anchor-rods extending upwardly from the anchors, turnbuckles connecting the anchor-rods to the tie-rods, anchor-plates embedded in the grade outside of the rails and turnbuckles connecting the anchor-plates to the ties.

6. In a railway-bed construction, a suitable grade, ties laid end to end upon the grade, rails upon the ties, tie-rods connecting the rails, anchors embedded in the grade, and elastic anchor-rods extending upwardly from the anchors and connected to the rails, substantially as specified.

7. In a railway-bed construction, a suitable grade, ties laid end to end upon the grade, rails upon the ties, tie-rods connecting the rails, anchors embedded in the grade, and elastic rods connecting the anchors to the tie-rods, substantially as specified.

35 8. In a railway-bed construction, a suitable grade, ties laid end to end upon the grade, rails upon the ties, tie-rods connecting the rails, anchors embedded in the grade, and adjustable rods connecting the anchors to the tie-rods, substantially as specified.

9. In a railway-bed construction, a suitable grade, ties upon the grade, rails upon the ties, anchors embedded in the grade, and elastic connections between the anchors and the ties, substantially as specified.

40 10. In a railway-bed construction, a suitable grade, ties upon the grade, rails upon the ties, anchors embedded in the grade, and adjustable connections between the anchors and the ties, substantially as specified.

45 In testimony whereof I have signed my name to this specification in presence of two subscribing witnesses.

ROBERT E. SMITH.
